COMBINED GAS INLET CONDUIT AND ELECTRODE FOR LIQUID CONVEYING APPARATUS
Compere Loveless, Overland Park, Kans., assignor to
Union Tank Car Company, a corporation of New JerseyContinuation of application Ser. No. 169,449, Jan. 29, 1962. This application Feb. 10, 1964, Ser. No. 343,816
11 Claims. (Cl. 137—209)

This application is a continuation of my application Serial No. 169,449, filed January 29, 1962, now abandoned.

This invention relates to electrode structure, and more particularly, to a material-sensing electrode for use in material-handling apparatus utilizing pressurized fluid for material ejecting purposes.

It is well known to utilize a normally open electrical control circuit in material-handling apparatus of this type with the circuit including a material level sensing electrode extending into a material receiver to be engaged by the material when the latter reaches a predetermined accumulation. Upon contact of the electrode by the material, the control circuit is closed through the material from the electrode to the "grounded" walls of the receiver to thereby effect introduction of pressurized fluid into the receiver to force the material out of the same.

Heretofore difficulties have been encountered with electrodes employed for the purposes specified because of rapid deterioration of the electrodes and the tendency for some material to cling to each of the electrodes and make contact with the wall of the respective receiver to hold the control circuit closed even after the initial accumulation of material in the receiver has been forced therefrom by the pressurized fluid. This problem has been especially acute where the material handled is of semiliquid characteristics and containing relatively stringy particles.

Various attempts have been made in the past to avoid the problems set forth, but they have been generally unsuccessful or have led to other problems which detracted from the overall successful operation of the apparatus. Specifically, attempts have been made to prevent the clinging of material to the electrode by directing air onto the electrode to clean the material therefrom following contact therewith by the material. Although the air usually was successful in cleaning the electrode, it was necessary to have an air nozzle mounted in the receiver directed toward the electrode or to mount the electrode in the conduit for conveying pressurized fluid to the receiver with the tip of the electrode extending beyond the conduit. This latter construction required the use of a relatively small electrode to prevent undue restriction of the fluid conduit. Increased current density from the small electrode caused a relatively short life to the electrode tip because of electrolysis which occurred to "plate out" certain elements from the material as deposits on the electrode.

Accordingly, it is the primary object of the present invention to provide electrode structure which may be maintained in a clean condition by the flow of pressurized fluid into the material receiver, yet not being subject to the disadvantages mentioned above.

Another important object, and in the achievement of the foregoing object, is the provision of tubular electrode structure which may be utilized as a conduit for transmitting pressurized fluid into the receiver and which serves as an efficient material-sensing element maintained in a clean condition by such flow of fluid.

Still a further important object of this invention is the

2

provision of electrode structure having a relatively large surface to be engaged by the material so that the current density on the electrode is kept to a minimum to retard the effects of electrolysis on the electrode and thus increase the useful life thereof.

Another object of this invention is the provision of an electrode having replaceable material-engaging components so that the electrode structure can be quickly and easily restored to original effectiveness after deterioration has occurred.

A still further object of the instant invention is the provision of electrode structure which can be conveniently cleaned with a brush or the like without the necessity of removing the structure from its installed position.

Yet another object of the invention is to eliminate the necessity for separate electrode and fluid introduction components in the apparatus so that substantial savings may be effected in both cost and required space.

In the drawing:

FIGURE 1 is a vertical, cross-sectional view of material-handling apparatus incorporating electrode structure embodying the principles of the instant invention; and

FIG. 2 is an enlarged, fragmentary, elevational view of the electrode structure with parts broken away and appearing in cross section to reveal details of construction.

Briefly, this invention relates to an electrode for sensing a predetermined accumulation of material in a receiver and for initiating a subsequent handling operation through the closing of a normally open electrical control circuit.

30 The electrode comprises an elongated tube of electrically conductive material extending into the receiver in a position to be engaged by the material. The electrode is insulated from the receiver by a jacket of electrically non-conductive protective material and is electrically coupled with one side of the control circuit. A source of pressurized fluid is coupled with the receiver for use in the handling operation through the tubular electrode by means of at least one electrically nonconductive fitting. Flow of fluid through the electrode maintains the latter free from clinging particles of material.

The electrode may be adjusted to any desired position of extension into the receiver by a ring of compressible material in releasable frictional engagement with the protective material and supported by a coupling assembly mounted on the material receiver. A replaceable tip at the end of the electrode structure permits ready replacement when the original tip becomes deteriorated from use.

The novel electrode structure of the present invention shown in detail in FIG. 2 and broadly designated 10 is particularly adapted for use with material-handling apparatus broadly numerated 12 and illustrated in FIG. 1. Apparatus 12 comprises structure for handling material such as sewage, and includes an inlet 14 adapted to be coupled to a source (not shown) of material for gravitation through inlet 14, past gate valve 16, check valve 18 (shown only schematically), through a T section 20 and into a closed material-receiving receptacle 22 through an inlet pipe 24. The latter is in communication with a material discharge pipe 26 through a check valve 28 and a second gate valve 30. In addition to receptacle 22, apparatus 12 includes an upper, open top chamber 32, and a closed middle compartment 34. A removable cover 36 is disposed to close chamber 32.

Structure 10 extends through compartment 34 and into receptacle 22 and comprises an elongated, tubular electrode 38 of electrically conductive material having an outer coating or sleeve 40 of electrically nonconductive material such as a synthetic resin. A thermoplastic resin such as a heat-shrinkable vinyl material is suitable for this purpose inasmuch as it may be disposed around electrode 38 and subjected to heat treatment causing the coat-

ing 40 to shrink and adhere quite closely to the outer surface of electrode 38. The end of electrode 38 which extends into receptacle 22 through a wall 42 comprising the bottom of compartment 34 and the top of the receptacle 22, is internally threaded and complementally receives a tubular tip element 44 also of electrically conductive material. Preferably, coating 40 extends slightly beyond the end of electrode 38 and over the outer surface of element 44 as shown in FIG. 2.

The electrode structure 10 extends from within receptacle 22 entirely through compartment 34 and beyond the upper wall 46 thereof and into chamber 32 as shown in FIG. 1. The structure 10 is carried by wall 42 by means of coupling apparatus 47 and including an upwardly extending, cylindrical flange 48 surrounding an aperture 49 in wall 42 through which structure 10 passes. Flange 48 is rigidly secured to wall 42 by any suitable means such as by welding and has an enlarged section 50 thereof having a threaded outer surface and a generally frustoconical, relatively smooth inner surface 52 of greatest diameter at the outer margin thereof remote from wall 42.

An annular member 54 of compressible material having a rim section 56 of generally triangular, transverse cross section, has its outer surface shaped to complementally engage the inclined inner surface 52 of enlarged section 50, and has a generally dome-shaped portion 58 disposed to be engaged by the concave inner surface 60 of a cup-shaped coupler broadly designated 62 in FIG. 2.

Coupler 62 is provided with a threaded inner surface threadably engaging the outer surface of enlarged section 50 and is provided with an irregular outer surface 64 suitably configured to receive a tool for turning coupler 62. The rotation of coupler 62 to tighten the latter on flange 48, squeezes member 54 between surface 52 and coupler 62 to force the inner surface of member 54 into tight frictional engagement with sleeve 40 on structure 10 and to thereby secure the latter in place. Also, member 54 serves as a fluid-tight seal to prevent the flow of fluid from within receptacle 22 for a purpose to be made clear hereinafter.

Coupling apparatus 66 secured to wall 46 and identical with apparatus 47, cooperates with the latter in supporting structure 10. Thus, apparatus 66 provides a fluid-tight seal to permit structure 10 to pass through wall 46 without the possibility of the escape of fluid from compartment 34.

A contact 68 connected to electrode 38 extends outwardly through coating 40 and is adapted to be electrically coupled to a switch box 72 by a line 70 shown in FIG. 1. Switch box 72 is connected to a source of power (not shown) and an electrically responsive 3-way valve 74 by a line 76. Valve 74 is operably coupled to a pipe 78 which communicates with a main air line 80 through a T 82. One end of air line 80 is operably coupled with an air compressor unit 84 which forms no part of the invention per se and is illustrated only schematically. The other end of air line 80 extends into compartment 34 and terminates in spaced relationship from wall 42 with seal 86 around line 80 adjacent wall 46 serving to prevent escape of fluid from compartment 34 around line 80. A pipe 88 connected to valve 74 and extending out of compartment 32 communicates the receptacle 22 with the atmosphere when the valve 74 is at one position thereof, while a nipple 90 communicates valve 74 with structure 10 through a T 92, as shown in FIG. 1, or alternatively through an elbow 94 as shown in FIG. 2. It should be pointed out that either T 92 or elbow 94 may be utilized for the purpose of communicating nipple 90 with structure 10. However, it may be desirable in some instances, to utilize T 92 in order to have available the upwardly extending opening therein which is normally closed by a plug 96. Both T 92 and elbow 94 are preferably constructed from electrically nonconductive material such as polyvinyl chloride or the like for a purpose to be made clear hereinafter.

In operation, apparatus 12 is disposed in a position to receive material to be handled and is conventionally installed underground in an upright position as shown in FIG. 1. Inlet 14 receives material such as sewage or the like which gravitates through check valve 18 and into receiver 22 where it is allowed to accumulate until the material contacts the tip element 44 of electrode structure 10. This completes the electrical control circuit coupled to valve 74, thereby resulting in the operation of certain switching components (not shown) in switch box 72 to effect electrical operation of valve 74. Valve 74 is shifted to terminate the normal communication of receptacle 22 to the atmosphere through electrode 38, T 92, pipe 90, the valve body of valve 74, and pipe 88 and to place compartment 34 into communication with receptacle 22. A supply of pressurized fluid which is normally maintained within compartment 34 by means of compressor 84, is permitted to flow through pipe 78, valve 74, nipple 90, T 92, electrode 38, tip 44 and into receiver 22 to forcibly eject the material therefrom that has accumulated in the same with the material being forced from receptacle 22 through pipe 24, past check valve 28 and through outlet pipe 26 to a sewage discharge line or the like. When receiver 22 has been emptied of material, valve 74 may be shifted through the operation of a timer, within switch box 72, to its normal position, again placing nipple 90 in communication with pipe 88 for communicating receiver 22 with the atmosphere and preventing the flow of pressurized fluid from compartment 34 into electrode 38.

The tubular construction of electrode 38 permits the utilization of the latter for the dual purpose of serving as a conductor in the electrical control circuit, and for conducting the fluid into receptacle 22. Any tendency of particles in the material to cling to the electrode following engagement thereof by the material, is overcome by the force of the compressed fluid passing through electrode 38 during the ejection cycle. The blast of such fluid as it enters the receptacle 22 through electrode 38, quite effectively cleans the material from the latter. This avoids a build-up of material on the electrode or the clinging of material to the electrode in bridging relationship to the latter and the side wall of receptacle 22 which would prevent reopening of the control circuit and thereby change of condition of the valve 74.

The relatively large surface area of tip element 44 made possible through the use of a tubular electrode, minimizes the current density on such surface when current is flowing through the control circuit, and accordingly, greatly reduces the accumulation of deposits on the element from the material because of the electrolysis which take place during current flow. This greatly increases the usable life of the tip elements. Additionally, the releasable attachment of element 44 to electrode 38, permits ready replacement of the element without the necessity for complete replacement of the electrode when the element 44 has deteriorated through use.

A further and very important advantage accrues through the use of novel electrode structure of this invention. Should the surface at the end of electrode 38 become fouled or coated so that electrical current cannot flow through the control circuit when the material physically contacts the electrode, the material will merely rise in the tubular electrode until it reaches a clean portion of the surface. When the material reaches the clean portion, electrical contact is established between the electrode and the material to close the control circuit and initiate the emptying of the receiver.

Thus, the tubular configuration of electrode 38 presents a substantially unlimited amount of available electrode surface to which the material will be conducted if the marginal surface of the electrode becomes fouled. This completely eliminates the possibility of failure of the material-handling apparatus to go through its ejection cycle because of deposits or coatings on the electrode

surface. The utilization of T 92 or elbow 94 of electrically nonconductive material, insulates electrode 38 from the other metallic components of the apparatus but permits fluid coupling of electrode 38 for the purpose of admitting compressed fluid into receiver 22. If a T 92 is used as shown in FIG. 1, additional cleaning operations on electrode 38 and tip 44 may be conducted by simply removing plug 96 from T 92 and inserting a brush in electrode 38. This operation may be conveniently carried out without the necessity for removal of electrode structure 10 from its installed position and without the necessity for a workman entering any part of the apparatus other than chamber 32.

The closely adhering, outer coating 40 on electrode 38 serves to protect the latter and to electrically isolate electrode 38 from walls 42 and 46. Additionally, coating 40 further serves to prevent any inadvertent contact between electrode 38 and other components of the apparatus.

Electrode structure 10 may be shifted upwardly or downwardly to vary the degree of extension of electrode 38 into receptacle 22 by the simple expedient of loosening coupling apparatuses 47 and 66 to permit the shifting of structure 10 either upwardly or downwardly. Apparatuses 47 and 66 may then be again tightened to effect a fluid-tight seal on compartment 34.

Although electrode structure 10 of this invention is shown in connection with its installation on sewage-handling apparatus, there is no intention to limit its use for such purposes. On the other hand, it will be readily understood that electrode structure 10 will have particularly advantageous utilization in any installation where it is necessary to have a material-sensing electrode to be engaged by the material and where it is desired to introduce fluid into a material container.

Although only one embodiment of the invention has been illustrated, those skilled in the art will realize that various changes and modifications may be made without departing from the spirit and scope of my invention, and it is intended that the appended claims cover all equivalent ramifications thereof.

Having thus described the invention, what is claimed as new and desired to be secured by Letters Patent is:

1. In apparatus for pneumatically conveying liquid material containing surface-adhering solids, such as sewage and the like, comprising:

- (A) an electrically grounded receptacle for accumulating said material and having a material inlet and a material outlet;
- (B) a source of pressurized gas and a gas inlet conduit to said receptacle for ejecting said material through said outlet;
- (C) an electrical circuit comprising a source of electrical energy, an electrode for sensing a predetermined level of said material, and electrically energized means for controlling flow of said pressurized gas; and
- (D) the improvement wherein said gas inlet conduit and electrode are combined to comprise:

(1) hollow tubular means including an electrically conductive end extending into said receptacle,

(2) means electrically insulating said end from said receptacle,

(3) means connecting the interior of said hollow tubular means to said source of pressurized gas,

(4) said hollow tubular means having an interior diameter large enough to admit pressurized gas into said receptacle at a rate sufficient to eject said material from said apparatus, said pressurized gas also serving to remove adhering solids from said end, and

(5) means electrically connecting the interior of said end to said circuit so as to complete said

75

circuit by grounding through material above said predetermined level contacting an electrode surface, defined by the interior of said end, of sufficient area to increase the life thereof by promoting low current density.

2. In apparatus for pneumatically conveying liquid material containing surface-adhering solids, such as sewage and the like, comprising:

- (A) an electrically grounded receptacle for accumulating said material and having a material inlet and a material outlet;
- (B) a source of pressurized gas and a gas inlet conduit to said receptacle for ejecting said material through said outlet;
- (C) an electrical circuit comprising a source of electrical energy, an electrode for sensing a predetermined level of said material, and electrically energized means for controlling flow of said pressurized gas;
- (D) the improvement wherein said gas inlet conduit and electrode are combined to comprise:
  - (1) hollow tubular means of electrically conductive material having an end extending into said receptacle,
  - (2) means electrically insulating said hollow tubular means from said receptacle,
  - (3) means connecting the interior of said hollow tubular means to said source of pressurized gas,
  - (4) said hollow tubular means having an interior diameter large enough to admit pressurized gas into said receptacle at a rate sufficient to eject said material from said apparatus, said pressurized gas also serving to remove adhering solids from said hollow tubular means, and
  - (5) means electrically connecting the interior of said hollow tubular means to said circuit so as to complete said circuit by grounding through material above said predetermined level contacting an electrode surface, defined by the interior of said end, of sufficient area to increase the life thereof by promoting low current density.

3. In apparatus for pneumatically conveying liquid material containing surface-adhering solids, such as sewage and the like, comprising:

- (A) an electrically grounded receptacle for accumulating said material and having a material inlet and a material outlet;
- (B) a source of pressurized gas and a gas inlet conduit to said receptacle for ejecting said material through said outlet;
- (C) an electrical circuit comprising a source of electrical energy, an electrode for sensing a predetermined level of said material, and electrically energized means for controlling flow of said pressurized gas;
- (D) the improvement wherein said gas inlet conduit and electrode are combined to comprise:

(1) hollow tubular means of electrically conductive material having an end extending into said receptacle, said end being separable from the remainder of said hollow tubular means so as to be replaceable on deterioration thereof,

(2) means on the exterior of said hollow tubular means electrically insulating same from said receptacle,

(3) means connecting the interior of said hollow tubular means to said source of pressurized gas,

(4) said hollow tubular means having an interior diameter large enough to admit pressurized gas into said receptacle at a rate sufficient to eject said material from said apparatus, said pressurized gas also serving to remove adhering solids from said hollow tubular means, and

(5) means electrically connecting the interior of

said hollow tubular means to said circuit so as to complete said circuit by grounding through material above said predetermined level contacting an electrode surface, defined by the interior of said end, of sufficient area to increase the life thereof by promoting low current density.

4. In apparatus for pneumatically conveying liquid material containing surface-adhering solids, such as sewage and the like, comprising:

- (A) an electrically grounded receptacle for accumulating said material and having a material inlet and a material outlet;
- (B) a source of pressurized gas and a gas inlet conduit to said receptacle for ejecting said material through said outlet;
- (C) an electrical circuit comprising a source of electrical energy, an electrode for sensing a predetermined level of said material, and electrically energized means for controlling flow of said pressurized gas;
- (D) the improvement wherein said gas inlet conduit and electrode are combined to comprise:
  - (1) hollow tubular means of electrically conductive material having an end extending into said receptacle,
  - (2) means electrically insulating said hollow tubular means from said receptacle,
  - (3) means connecting the interior of said hollow tubular means to said source of pressurized gas,
  - (4) means electrically connecting the interior of said hollow tubular means to said circuit so as to complete said circuit by grounding through material above said predetermined level contacting an electrode surface defined by the interior of said end, and
  - (5) a portion of said hollow tubular means outside of said receptacle having an access opening permitting cleaning of solids adhering to the interior of said end without entering said receptacle.

5. The invention defined in claim 4 wherein said tubular means is substantially straight between said access opening and said end.

6. The invention defined in claim 4 wherein said tubular member is generally vertical and said access opening extends upwardly.

7. In apparatus for pneumatically conveying liquid material containing surface-adhering solids, such as sewage and the like, comprising:

- (A) an electrically grounded receptacle for accumulating said material and having a material inlet and a material outlet;
- (B) a source of pressurized gas and a gas inlet conduit to said receptacle for ejecting said material through said outlet;
- (C) an electrical circuit comprising a source of electrical energy, an electrode for sensing a predetermined level of said material, and electrically energized means for controlling flow of said pressurized gas;
- (D) the improvement wherein said gas inlet conduit and electrode are combined to comprise:
  - (1) hollow tubular means of electrically conductive material having an end extending into said receptacle,
  - (2) means electrically insulating said hollow tubular means from said receptacle,
  - (3) electrical insulating means covering the entire exterior of said end inside said receptacle,
  - (4) means connecting the interior of said hollow tubular means to said source of pressurized gas, and
  - (5) means electrically connecting the interior of said hollow tubular means to said circuit so as

to complete said circuit by grounding through material above said predetermined level contacting an electrode surface defined by the interior of said end.

8. In apparatus for pneumatically conveying liquid material containing surface-adhering solids, such as sewage and the like, comprising:

- (A) an electrically grounded receptacle for accumulating said material and having a material inlet, a material outlet and an upper wall;
- (B) a source of pressurized gas and a gas inlet conduit to said receptacle for ejecting said material through said outlet;
- (C) an electrical circuit comprising a source of electrical energy, an electrode for sensing a predetermined level of said material, and electrically energized means for controlling flow of said pressurized gas;
- (D) the improvement wherein said gas inlet conduit and electrode are combined to comprise:
  - (1) downwardly extending hollow tubular means of electrically conductive material having an end passing through said upper wall and into said receptacle,
  - (2) means electrically insulating said hollow tubular means from said receptacle,
  - (3) means connecting the interior of said hollow tubular means to said source of pressurized gas, and
  - (4) means electrically connecting the interior of said hollow tubular means to said circuit so as to complete said circuit by grounding through material above said predetermined level contacting an electrode surface defined by the interior of said end, the interior of said hollow tubular means above said wall being an extension of said electrode surface, whereby malfunctioning of said apparatus caused by solids adhering to said end is prevented by liquid rising to a clean area on said extension.

9. In apparatus for pneumatically conveying liquid material containing surface-adhering solids, such as sewage and the like, comprising:

- (A) an electrically grounded receptacle for accumulating said material and having a material inlet and a material outlet;
- (B) a source of pressurized gas and a gas inlet conduit to said receptacle for ejecting said material through said outlet;
- (C) an electrical circuit comprising a source of electrical energy, an electrode for sensing a predetermined level of said material, and electrically energized means for controlling flow of said pressurized gas;
- (D) the improvement wherein said gas inlet conduit and electrode are combined to comprise:
  - (1) hollow tubular means of electrically conductive material having an end extending into said receptacle,
  - (2) means electrically insulating said hollow tubular means from said receptacle,
  - (3) electrical insulating means covering the entire exterior of said end inside said receptacle,
  - (4) means connecting the interior of said hollow tubular means to said source of pressurized gas, and
  - (5) means electrically connecting the interior of said hollow tubular means to said circuit so as to complete said circuit by grounding through material above said predetermined level contacting an electrode surface defined by the interior of said end, the interior of said hollow tubular means above said end being an extension of said electrode surface, whereby malfunctioning of said apparatus caused by solids adhering to the interior of said end is prevented by liquid rising to a clean area on said extension.

10. In apparatus for pneumatically conveying liquid material containing surface-adhering solids, such as sewage and the like, comprising:

- (A) an electrically grounded receptacle for accumulating said material and having a material inlet and a material outlet;
- (B) a source of pressurized gas and a gas inlet conduit to said receptacle for ejecting said material through said outlet;
- (C) an electrical circuit comprising a source of electrical energy, an electrode for sensing a predetermined level of said material, and electrically energized means for controlling flow of said pressurized gas;
- (D) the improvement wherein said gas inlet conduit and electrode are combined to comprise:
  - (1) hollow tubular means of electrically conductive material having an end extending into said receptacle, said end being separable from the remainder of said hollow tubular means so as to be replaceable on deterioration thereof,
  - (2) means on the exterior of said hollow tubular means electrically insulating same from said receptacle,
  - (3) electrical insulating means covering the entire exterior of said end inside said receptacle,
  - (4) means connecting the interior of said hollow tubular means to said source of pressurized gas,
  - (5) means electrically connecting the interior of said hollow tubular means to said circuit so as to complete said circuit by grounding through material above said predetermined level contacting an electrode surface defined by the interior of said end, and
  - (6) a portion of said hollow tubular means outside of said receptacle having an access opening permitting cleaning of solids adhering to the interior of said end without entering said receptacle, said tubular means being substantially straight between said access opening and said end.

11. In apparatus for pneumatically conveying liquid material containing surface-adhering solids, such as sewage and the like, comprising:

- (A) an electrically grounded receptacle for accumulating said material and having a material inlet and a material outlet;
- (B) a source of pressurized gas and a gas inlet conduit to said receptacle for ejecting said material through said outlet;
- (C) an electrical circuit comprising a source of elec-

45

trical energy, an electrode for sensing a predetermined level of said material, and electrically energized means for controlling flow of said pressurized gas;

- (D) the improvement wherein said gas inlet conduit and electrode are combined to comprise:
  - (1) generally vertical hollow tubular means of electrically conductive material having an end extending into said receptacle, said end being separable from the remainder of said hollow tubular means so as to be replaceable on deterioration thereof,
  - (2) means electrically insulating said hollow tubular means from said receptacle,
  - (3) electrical insulating means covering the entire exterior of said end inside said receptacle,
  - (4) means connecting the interior of said hollow tubular means to said source of pressurized gas,
  - (5) said hollow tubular means having an interior diameter large enough to admit pressurized gas into said receptacle at a rate sufficient to eject said material from said apparatus, said pressurized gas also serving to remove adhering solids from said hollow tubular means,
  - (6) means electrically connecting the interior of said hollow tubular means to said circuit so as to complete said circuit by grounding through material above said predetermined level contacting an electrode surface, defined by the interior of said end, of sufficient area to increase the life thereof by promoting low current density, the interior of said hollow tubular means above said end being an extension of said electrode surface, whereby malfunctioning of said apparatus caused by solids adhering to the interior of said end is prevented by liquid rising to a clean area on said extension, and
  - (7) a substantially straight portion of said hollow tubular means outside of said receptacle having an upwardly extending access opening permitting cleaning of solids adhering to the interior of said end without entering said receptacle.
